[57] **CLAIM**

The ornamental design for a tower mounted amplifier, as shown and described.

DESCRIPTION

FIG. 1 is a perspective view of a tower mounted amplifier showing our new design.

FIG. 2 is a top plan view thereof;

FIG. 3 is a bottom plan view thereof;

FIG. 4 is a side elevational view of one side thereof, the opposite side being a mirror image thereof;

FIG. 5 is a front elevational view thereof; and,

FIG. 6 is a rear elevational view thereof.

The broken line shown in FIG. 3 is for illustrative purposes only and forms no part of the claimed design.
